JAMES F. COLGAN, OF PROVIDENCE, RHODE ISLAND, ASSIGNOR TO CROMPTON & KNOWLES LOOM WORKS, OF WORCESTER, MASSACHUSETTS, A CORPORATION OF MASSACHUSETTS

SHUTTLE-BOX CONSTRUCTION FOR LOOMS

Application filed December 20, 1928. Serial No. 327,340.

This invention relates to improvements in the construction of shuttle boxes for looms and it is the general object of the invention to provide an improved mounting for the box plate to the end that it may be aligned properly with the lay of the loom.

In looms employing wooden lays it is common practice to screw the box plate directly to the upper face of the lay wood. It is naturally a difficult matter to secure correct alignment because of the fact that the wood does not always retain its shape. It is common to employ shims which are placed between the box plate and the lay wood so that the plate may be properly aligned with the race plate of the lay. This operation is tedious and requires considerable fitting, with a complete removal of the box plate from the lay several times during the operation. It is an important object of my present invention to provide means to hold the box plate to the lay in correct alignment without the use of shims, etc.

Wood screws are ordinarily employed to fasten the plate to the lay wood and it is a further object of my present invention to combine with these wood screws other screws which do not pass through the box plate but which are held in position by the lay to define a plurality of spaced rests or adjustable supports on which the box plate may rest. In order that there may be as little internal stress set up in the box plate as possible I preferably secure the screws closely together in pairs, each pair having one screw to pass through the box plate into the lay wood and another closely adjacent a screw secured to the lay but adapted to form one of the supporting points for the bottom of the box plate.

With these and other objects in view which will appear as the description proceeds, my invention resides in the combination and arrangement of parts hereinafter described and set forth in the claims.

In the accompanying drawings wherein I have shown two forms of my invention,

Fig. 1 represents a top plan view of one end of the lay showing a bottom box plate and showing its preferred form of attachment to the lay wood,

Fig. 2 is a section on line 2—2 of Fig. 1,

Fig. 3 is an enlarged vertical section on line 3—3 of Fig. 1, and

Fig. 4 is a fragmentary vertical section similar to a portion of Fig. 2 but showing the modified form of box plate support.

The present invention relates to the box plate and it is deemed sufficient to illustrate the same in connection with the lay without showing other parts of the loom, such for instance as the picking mechanism to propel the shuttle out of the box or the driving mechanism to cause reciprocations of the lay. The lay may include the lay beam 10 which is supported by swords one of which is indicated at 11. As viewed in Fig. 2 the cloth will lie to the left of the sword 11 while the shuttle when properly boxed during beat-up will lie to the right of the sword. As shown in Fig. 3 I have provided a box plate 12 having a box back 13 and a binder 14. The plate as shown in Fig. 1 may have a longitudinal slot 15 for the passage of the expelled bobbin of a depleted shuttle when the lay is used in connection with weft replenishing looms. The binder may move around a stud 16 which is carried by the plate. The form of the lay wood and also the box plate and parts carried by the latter to define the shuttle box may be of usual construction and of themselves form no part of my present invention.

The box plate is held to the upper surface of the lay by means of a plurality of wood screws 20, these wood screws being the same for both the preferred and modified form of the invention. Said screws are located in counter-sunk holes 21 so as to offer no re-

sistance to the flight of the shuttle which it will be understood moves across the top surface 22 of the box plate.

My invention relates more particularly to provision for improved means to engage the under surface 23 of the box plate 12 and in carrying my invention into effect in its preferred form I provide closely adjacent each of the screws 20 a wood screw 30 which projects upwardly slightly from the top surface 31 of the lay wood. These screws 30 may be adjusted as to height and are the effective supports for the box plate. It will be seen by reference to Fig. 2 that there may be a slight space between the upper surface 31 of the lay wood and the under side 23 of the box plate.

As suggested in Fig. 1 the screws 20 and 30 are grouped in pairs so that there will be as little strain on the box plate as possible due to downward pressure exerted by the wood screws 20. In applying a box plate to a loom according to the preferred form of my invention the plate will be applied to the lay and gauged to determine its position with respect to the race plate 40 which lies between the swords and along which a shuttle normally runs. If it is found for instance that the box plate is too high so that a shuttle upon arriving at the box is given an abrupt upward movement to cause wear on its lower surface, the screws 30 may be turned down until they are placed so as to give the box plate its proper relation with respect to the race plate, after which the wood screws 20 will be screwed tightly into the lay wood.

Fig. 4 shows a modified form of the invention wherein all of the elements are the same as in the preferred form with the exception of the screws which form the points of support for the box plate. As shown in Fig. 4 there is extending through the lay wood a plurality of screws 50 preferably of the machine type. The upper ends of said screws are provided with heads 51 on which the lower surface 23 of the box plate rests. Said screws 50 are sufficiently long to be accessible from the under side of the lay and each screw is provided with a check nut 52. If desired the lower end of each screw 50 may be formed with a small square head 53 by means of which the screw may be turned, but I do not wish to be limited to this means for rotating the screws 50.

In the operation of the modified form of my invention adjustment of the upper surface of the box plate may be effected without removing the latter from the lay merely by loosening the check nuts 52 and the wood screws 20 and moving the screws 50 until the upper surface 22 is properly related to the race plate. The check nuts 52 may then be tightened and the wood screws 20 driven into the lay wood. It will be noted in the modified form that it is not necessary to re-

move the box plate from the lay while the adjustments are being made.

Reference to Fig. 1 shows that the pairs of screws are arranged in two rows, one near the rear edge 60 of the box plate and the other near the front edge 61. Because of the fact that the adjusting screws are located at different points transversely of the lay, I am able to adjust the box plate by moving it in a plane transverse of the lay.

From the foregoing it will be seen that I have provided a very simple means for supporting a box plate on the loom lay, said means presenting a plurality of points fixed with respect to the lay wood and independent of the upper surface of the lay wood, said points being readily adjustable to determine the location of the upper surface of the box plate. It will also be seen that the positioning and retaining screws are located preferably in pairs so as to effect as little internal straining of the box plate as possible. It will further be seen with respect to the modified form of the invention that the box plate may be adjusted without removing the same from the lay. This is particularly desirable in the use of looms which have been in use for some time and wherein a slight twisting of the lay wood throws the box plate out of proper relation with respect to the race plate. Under these conditions it would be a comparatively simple matter either to raise or lower the screws 50 without removing the box plate from the loom. Furthermore, the elements such as the box back 13 and the binder 14 which assist in defining the shuttle box are also located with respect to the positioning screws so that the shuttle box as a whole may be adjusted as to vertical position relatively to the lay by means of my present invention. It will further be seen that by arranging some of the screws along the rear edge and others along the front edge of the box plate I am able to vary the angular relation of the box plate with respect to the lay and the race plate in a direction transversely of the lay.

While the invention has been described herein before with particular reference to the box plate which forms the bottom of the shuttle box, certain features of the invention are not necessarily limited to this part of the shuttle box.

Having thus described my invention it will be apparent that changes and modifications may be made therein by those skilled in the art without departing from the spirit and scope of the invention and I do not wish to be limited to the details herein disclosed, but what I claim is:

1. In a loom lay, a bottom box plate, a plurality of positioning elements normally fixed to the lay but movable with respect thereto and forming points of support for the bottom

box plate, and means to hold said plate against said elements.

2. In a loom lay, a bottom box plate, a plurality of positioning elements supported by the lay and movable with respect to the latter in a direction substantially perpendicular to the bottom box plate and capable of assuming a plurality of positions relatively to the lay, and means to hold said plate against said elements.

3. In a loom lay, a bottom box plate, a plurality of positioning elements supported by the lay and movable with respect to the latter in a direction substantially perpendicular to the bottom box plate and capable of assuming a plurality of positions relatively to the lay, and means to hold said plate against said elements, said means extending through said plate and into the lay.

4. In a loom lay, a bottom box plate, a plurality of screws extending upwardly from the lay and capable of assuming a plurality of positions relatively to the lay in a vertical direction, said screws defining points of support for the bottom box plate, and means to hold said plate against said screws.

5. In a loom lay, a bottom box plate, retaining screws passing through the bottom box plate and into the lay, and positioning screws carried by and movable with respect to the lay and in engagement with the bottom box plate, said positioning screws forming points of support for the plate and the retaining screws holding said plate against the positioning screws.

6. In a loom lay, a bottom box plate, retaining screws passing through the bottom box plate and into the lay, and positioning screws carried by and movable with respect to the lay and in engagement with the bottom box plate, said positioning screws forming points of support for the plate and the retaining screws holding said plate against the positioning screws, each positioning screw being closely adjacent a retaining screw.

7. In a loom lay, a bottom box plate, retaining screws passing through the bottom box plate and into the lay, and positioning screws carried by and movable with respect to the lay and in engagement with the bottom box plate, said positioning screws forming points of support for the plate and the retaining screws holding said plate against the positioning screws, said positioning screws being accessible from the under side of the lay.

8. In a loom lay, a bottom box plate, positioning screws extending vertically through the lay and projecting below the under side of the latter, said screws being adjustable vertically in the lay and presenting points of support on which the bottom box plate rests, and means to hold the bottom box plate against said screws, the latter being accessible from the under side of the lay and being mov-

able with respect to the latter while said plate is in position on the lay.

9. In a loom lay, a bottom box plate, positioning elements movable with respect to the lay to support the bottom box plate, said elements being accessible and movable relatively to the lay while the said plate is in position on the lay, and means to hold said plate against the positioning elements.

10. In a loom lay, a bottom box plate, said bottom box plate having a front and a rear edge, a plurality of positioning elements extending into but movable with respect to the lay to engage the bottom box plate adjacent the rear edge of the plate, other positioning elements extending into but located adjacent the front edge of the bottom box plate, and means to hold said plate against said positioning means.

11. In a loom lay, a bottom box plate, said bottom box plate having front and rear longitudinal edges, positioning means movable with respect to the lay in a direction toward and from the bottom box plate and located near the rear edge of the plate, additional positioning means movable with respect to and movable toward and from the bottom box plate, and means to hold said plate against the positioning means.

12. In a loom lay, a bottom box plate, a race plate for the lay, positioning means normally fixed with respect to the lay but movable in the latter in a direction transversely of the race plate, said positioning means defining a support for the bottom box plate to position the latter with respect to the race plate.

13. In a loom lay, a bottom box plate, binder and box back members to define with the plate a shuttle box, said members being supported by and moving with the plate, and positioning members in engagement with the bottom box plate and normally held fixed to the lay and supported by the latter but movable with respect to the lay to cause the bottom box plate and members to assume any one of a plurality of positions relatively to the lay.

14. In a loom lay, a shuttle box forming member extending longitudinally of the lay to engage the shuttle and assist in determining the direction of flight thereof, a plurality of spaced positioning elements arranged along the lay movable in a direction transverse of the path of movement of the shuttle, and a plurality of retaining means to hold the member against the elements, said positioning elements and retaining means being capable of moving the member as a whole and relatively to the path of movement of the shuttle in a direction transverse to the path of the shuttle.

15. In a loom lay having guide means along which the shuttle travels, a member supported by the lay to be engaged by and

guide the shuttle, and two separate instrumentalities coacting with each other and the member to hold the latter in position, said instrumentalities both being movable in the same direction and transversely of the guide means to give the member different positions relatively to the guide means and both being normally fixed relatively to the lay, one of said instrumentalities holding the member against the other and the latter determining the position of the member with respect to the guide means.

10 In testimony whereof I have hereunto affixed my signature.
